Patented Apr. 11, 1967

207,434

COVER FOR AN AEROSOL DISPENSER OR THE LIKE

Ellsworth R. Danz and Roman J. Szalek, La Salle, Ill.,
assignors to General Time Corporation, Stamford,
Conn., a corporation of Delaware

Filed July 8, 1966, Ser. No. 3,004

Term of patent 14 years

(Cl. D58—26)

FIG. 1

FIG.2

FIG.3

FIG.4

FIG. 6

FIG. 5

FIG. 1 is a perspective view of a cover for an aerosol dispenser showing the new design, with an aerosol can shown fragmentarily in broken lines for illustrative purposes only.

FIG. 2 is a top plan view of the cover.

FIG. 3 is a front elevational view of the cover.

FIG. 4 is a right side elevational view of the cover.

FIG. 5 is a rear elevational view of the cover.

FIG. 6 is a left side elevational view of the cover.

We claim:

The ornamental design for a cover for an aerosol dispenser or the like, substantially as shown and described.
